UNITED STATES PATENT OFFICE

RANDOLPH V. WELLER, OF ROCHESTER, NEW YORK, ASSIGNOR TO THE DEXTER COMPANY, OF FAIRFIELD, IOWA, A CORPORATION OF IOWA

IRONING MACHINE

Application filed September 27, 1926. Serial No. 137,875.

The present invention relates to ironing machines and more particularly to the type in which the iron and the bed are moved relatively through a power operated mechanism which is controlled through a member operated by the user of the machine. An object of the invention is to provide for rendering ineffective said controlling member when the hands of the user of the machine are positioning material between the bed and the iron.

To this and other ends, the invention consists of certain parts and combinations of parts, all of which will be hereinafter described; the novel features being pointed out in the appended claims.

In the drawings:

Fig. 1 is a perspective view of an ironing machine constructed in accordance with this invention;

Fig. 2 is a fragmentary sectional view showing the operating mechanism for the iron and the bed and the control thereof;

Fig. 3 is an enlarged sectional view showing the iron and the bed brought into cooperation and the locking mechanism free from the controlling mechanism permitting the operation of the latter;

Fig. 4 is a fragmentary view showing the iron and the bed out of cooperation and the controlling mechanism locked against operation; and

Fig. 5 is a fragmentary sectional view of an operating mechanism for the bed and the iron.

Many parts of the ironing machine shown in this application are shown in an application filed by me on September 24, 1925, Serial No. 58,434, but it will be understood that this invention is not limited to a machine of the type shown in said application, as I believe I am the first to provide a power driven ironing machine which has a controlling mechanism controlling the relative movement between an iron and the bed and adapted to be rendered ineffective by hands of the user of the machine when such hands are employed for positioning the material between the bed and the iron.

Attention is called to the above mentioned

application in order that if any of the known mechanisms which are shown in the present application are not clear, their construction and operation may be obtained by reference to the aforesaid application.

In the illustrated embodiment of the invention 1 indicates the frame of the machine which supports a receiving board or table 2, side pieces 3 and 4 projecting above the receiving table and supporting a feeding table

5. These sides also support a roller bed 6 with which cooperates a curved iron 7 in this instance pivoted at 8 below the bed and extending upwardly in rear of the latter.

Relative movement between the bed and the iron is effected in this instance by a double arm lever 9 pivoted at 10 to a support 11 and having one end secured to a locking burner tube 12 while the other end is pivotally connected at 13 to one end of a link

14, the other end of link 14 being connected at 15 to one end of a double arm lever 16. This double arm lever 16 is pivotally supported at 17 on a swinging link 18 and carries at its free end a roller 19 co-operating with a cam 20 on the shaft 21 journaled in the frame of the machine.

Aligned with the shaft 21 is a shaft 22 which carries a worm wheel 23 meshing with a worm 24 in this instance on the shaft of an electrical motor 25. Between the shaft 22 and the shaft 21 there is employed a clutch embodying, in this instance, a clutch member 26 formed with pockets 27 in one face thereof in which is adapted to be projected a plunger 28 guided in a member 29 and operated through a lever 30, a spring 32 acting on the lever to normally hold the plunger toward the member 26. The driving or turning of the bed 6 is effected, in

this instance, by providing gear teeth 33 on the member 26 to cooperate with gear teeth 34 on a shaft 35 journaled in a swinging frame 36 which is mounted to turn on the shaft 37 forming the shaft of the bed 6.

Also secured to the shaft 37 is a gear wheel 38 which meshes with a pinion 39 on the shaft 35 so that there is provided a train gearing extending between the shaft 22 and the shaft 37 of the bed 6 to turn the latter.

Connection between the shaft 37 and the shaft 22 is controlled in this instance by a cam 40 formed on the member 29 and co-operating with a roller 41 supported on the swinging frame 36, this cam 40 being so formed that at one point it permits the gears 33 and 34 to engage and at a diametrically opposite point it holds the gears 33 and 34 out of engagement.

Control of the clutch connection between the shaft 22 and the shaft 21 is effected in this instance through a slide 42 mounted on the side frame 4 and having two projections 43 and 44. These projections are adapted to cooperate with a cam 45 on the lever 30 to move the plunger 28 out of engagement with the clutch member 26. Assuming that the parts are in the position shown in Fig. 5 and the slide 42 is depressed while the iron is in cooperation with the bed and the bed is turning as shown in Fig. 3, then, with the depression of the projection 43, the lever 30 will move to shift the plunger 28 into engagement with the clutch member 26. This causes the shaft 21 to turn to move the iron away from the bed and at the same time the cam 40 is turned to shift the gear 34 out of engagement with the gear 33 thus stopping the turning of the bed 6. After this has been effected, the cam 45 engages the projection 44 and shifts the plunger 28 out of connection with the clutch member 26 thereby holding the iron away from the bed and driving the bed ceases.

The slide 42 before mentioned is pivotally suspended at 46 from a lever 47 which is pivoted at 48 to the side piece 4. A similar lever without the extension for the slide is arranged at the opposite end of the machine and these two levers support a controlling bar or member 49 which is arranged within a groove 50 in the feeding board 5. A spring 51 acts on one of these levers and holds the finger bar or controller 49 and the slide 42 in an elevated position with two projections 43 and 44 in the path of the cam 45 so that the depression of the bar 47 moves these projections out of the path of the cam 45.

The feature of this invention is the means which renders the controlling means for the power mechanism ineffective while the hand of the user of the machine is being employed for positioning material between the iron and the bed. In this instance, this result is accomplished by locking the controlling means against operation, this locking means preferably embodying a stop 52 mounted for movement beneath the upper end 53 of the lever 47, this stop in this instance being formed on one end of a bar 54 which is pivoted at 55 to an arm 56, this arm being mounted on the projecting end of a rod 57 extending through the iron and projected from both sides thereof, a similar arm 56

being mounted on the opposite end of the rod 57 and both arms 56 serving to support a controlling member 58 in the form of a bar extending substantially from one end of the iron to the other in advance of the upper edge thereof. When the iron and the bed are engaged, this control rod or bar 58 is held closely toward the bed 6 by a spring 59 which is anchored on the frame of the machine and at its other end to the bar 54, thus positioning the stop 52 out of the path of the end 53 of the lever 47 permitting the controlling or finger bar 49 to be depressed. When the user of the machine desires to position goods between the iron and the bed it is necessary that she introduce her fingers between the bar 58 and the bed 6 to move said bar upwardly and rearwardly away from the bed so as to clear the space between the bed and the iron. In doing this the bar 54 is shifted, bringing the stop 52 into the path of the projecting end 53 of the lever 47 thereby preventing the depression of the lever and consequently the depression of the finger bar 49. This effectively prevents the power mechanism being started through the controlling mechanism when the operator's hand lies between the iron and the bed during the positioning of material between such parts.

The operation of the ironing machine is as follows: The motor 25 drives the worm 24 which turns the worm wheel 23 and also the stub shaft 22 which has the combined clutch member and gear 26 and 33 rigidly secured thereto. The gear 33 drives the gear 34 which in turn drives the gear 39 meshing with the gear 38 on the shaft 37 of the rotary bed 6, thus effecting a rotation to the bed. The gear 34 is movable by means of the arm 36 into and out of engagement with the gear 33 so that connection between the gear 33 and the rotary bed may be broken. This is effected through the cam 40 on the stub shaft 21, the cam 45 engaging the roller 41 periodically and lifting the gear 34 away from the gear 33.

The pin or plunger 28 is adapted to enter one of the pockets or notches 27 in the combined clutch and gear 26 and 33 in order to establish connection between the shaft 22 and the shaft 21 so as to effect the rotation of the cam 40 which produces relative movement between the iron 7 and the bed 6. The control of the clutch is effected by two projections 43 and 44 on the slide 42, these projections engaging the cam surface 45 on the lever 30 which controls the clutch pin 28, the spring 32 normally holding the cam surface toward the slide to project the plunger 28. The slide is suspended from the lever 47 which is pivoted at 48 and which in turn has connections with the finger bar 49. The projections 43 and 44 lie normally in the path of rotation of the

cam 45 and the depression of the finger bar 49 moves these two projections out of the path of travel of the cam 45. As soon as the cam 45 engages with the projection 43 or 44, the clutch pin or plunger 28 is moved 5 out of engagement with the clutch member 26 and stops the cam 45 in engagement with one of the projections 43 or 44. As soon as the slide 42 is depressed, the projection 10 44 or 43 moves out of engagement with the cam 45 and permits the spring 32 to shift the clutch pin or plunger 28 into one of the pockets 27. By this time, the finger bar 49 is released and after the cam 45 has 15 moved a distance less than the one-half of a circle, the cam 45 will engage the other projection 43 or 44 and again releases the shaft 21 from the shaft 22. In other words, the shaft 21 is rotated 180° to the clutch 20 plunger 28 and is then released automatically by one of the projections 43 or 44 which holds the plunger 28 out of clutching position until the finger bar is again depressed. When the cam engages the projection 25 43, the gear 34 is in mesh with the gear 33, but when the cam 45 engages the projection 44, the gear 34 is lifted out of engagement with the gear 33. In other words, when the iron is in engagement with 30 the bed, the gears 33 and 34 are in mesh so as to rotate the bed, but when the iron is moved away from the bed, the bed and the gears 33 and 34 are out of engagement so that the bed is not rotated.

35 Movement of the iron is effected through the cam 20 which engages the roller 19 on the lever 18, its high point swinging the lever 18 in one direction to move the iron toward the bed and its low point permitting 40 the iron to move away from the bed. This lever 18 connects by a link 14 with a rocking arm 9 pivoted at 10 to the yieldingly supported member 11. The arm 9 rocks on the iron 7 which is pivoted at 8. All of 45 these above parts are shown and described in my prior application hereinbefore mentioned. Associated with this or equivalent mechanism is means for rendering such controlling means ineffective, comprising a dis- 50 placeable member 58 lying in front of the spring between the iron and the bed so that it must be displaced when the hand of the user is introduced between the iron and the bed. This bar is carried by arms 55 55 and pivoted at 57 to one of these arms is a member 54 which has a portion 52 movable in the path of the end 53 of the lever 47 so that the lever 47 cannot be depressed through the finger bar 49 to control the 60 clutch when a hand is introduced between the iron and the bed.

What I claim as my invention and desire to secure by Letters Patent is:

1. In an ironing machine, the combination 65 with a bed, an iron cooperating with the bed,

and power mechanism for effecting relative movement between the bed and the iron to bring them into and out of cooperation, of means under the control of the operator for controlling the power mechanism, a movable 70 member extending above the bed in advance of the iron, and adapted to be displaced by the hand of the user of the machine in introducing material between the bed and the iron, and means operated by said movable 75 member for locking the controlling means against movement when said movable member is displaced by the hand of a user in introducing material between the bed and the iron and the bed are separated. 80

2. In an ironing machine, the combination with a bed, an iron for cooperating with the bed, power mechanism for effecting relative movement between the bed and the iron, and means under the control of an operator for effecting the operation of the power mechanism, of a lock for holding said controlling means against movement, and a member extending substantially throughout the length 90 of the iron above the bed and in advance of the iron, said member being mounted to be displaced by the hand of a user of the machine in introducing material between the bed and the iron, and connection between 95 said member and the lock for locking the controlling means against movement when the said member is displaced and the iron and the bed are separated.

3. In an ironing machine, the combination 100 with a rotary bed, a curved iron mounted for movement toward and from the bed at the rear of the latter, power mechanism for effecting the movement of the iron toward and from the bed, and means under the control 105 of the operator of the machine for effecting the operation of the power mechanism, of a member movably mounted on the iron in advance of the upper end of the latter and over the bed so that it must be displaced by 110 the hand of the user of the machine in introducing material between the bed and the iron, and locking means controlled by said member for locking the controlling means 115 against movement when the member is displaced by the hand of a user in introducing material between the bed and the iron and the iron and the bed are separated.

4. In an ironing machine, the combination 120 with a rotary bed, a curved iron mounted for movement toward and from the bed in rear of the latter, and having its upper end projecting above the bed to provide an intake portion through which material may be introduced between the bed and the iron, power mechanism for effecting the movement of the iron toward and from the bed, and means under the control of the operator for effecting the operation of the power mechanism, of a member extending substantially 125 130

throughout the length of the iron in advance of the upper end of the latter and over the bed and mounted for movement on the iron, a bar connected to said member, and a lock shifted by said bar into and out of the path of the controlling means.

5. The combination with a bed and an iron, of power mechanism for effecting relative movement between them, an automatically operating make and break device for stopping the movement between them when they are in engagement and also when they are separated, an operative-operated controller for said make and break device to cause the power mechanism to effect the movement between the bed and the iron, a lock for holding said operative-operated controller against movement, and means for controlling the lock embodying a displaceable member lying outside of but in close proximity to the space between the bed and the iron so that it will be displaced upon the introduction of a hand between the bed and the iron when said elements are separated.

10 6. In an ironing machine, a rotary bed, a curved iron cooperating with the bed, and power mechanism for moving one of said elements into and out of engagement with the other, of automatic means for stopping such movement when the two elements are in cooperation and also are separated, operative-controlled means for starting such movement, a lock for the operative-controlled means, and means for operating the lock embodying a displaceable member supported by the iron in front of said space so that it must be displaced to introduce material between the bed and the iron.

RANDOLPH V. WELLER.
